(57) CLAIM

The ornamental design for an indoor sauna with windows, as shown and described.

DESCRIPTION

FIG. 1 is a perspective view of an indoor sauna with windows;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

With regard to the drawings presented, the broken lines are intended to depict environmental structure and/or portions of the indoor sauna with windows that form no part of the claimed design.

1 Claim, 7 Drawing Sheets
